(57) **CLAIM**

The ornamental design for a dorsal pad assembly for a safety harness, as shown and described.

DESCRIPTION

FIG. 1 is a perspective view of a dorsal pad assembly for a safety harness, showing my new design in use;

FIG. 2 is a front view thereof;

FIG. 3 is a rear view thereof;

FIG. 4 is a side view thereof;

FIG. 5 is another side view thereof;

FIG. 6 is a front view of the dorsal pad assembly, shown in an alternate configuration of use; and,

FIG. 7 is a rear view of the dorsal pad assembly shown in FIG. 6.

The broken lines in the drawing depict environmental subject matter only and form no part of the claimed design.
